FRANK H. WILLIAMS, OF BUFFALO, NEW YORK.

APPARATUS FOR MAKING SPIRAL-ROLLED BARS.

1,161,176.

Specification of Letters Patent. Patented Nov. 23, 1915.

Application filed September 29, 1913. Serial No. 792,273.

To all whom it may concern:

Be it known that I, FRANK H. WILLIAMS, a citizen of the United States of America, residing at Buffalo, in the county of Erie and State of New York, have invented certain new and useful Improvements in Apparatus for Making Spiral-Rolled Bars, of which the following is a full, clear, and exact description.

10 My invention relates generally to apparatus for making metal bars having spirally disposed threads, such as may be used in reinforcing concrete work.

As is well known to those skilled in the art, metal bars which have been used for reinforcing concrete have been formed with spiral threads by twisting the bars. These bars are generally of polygonal cross-section or formed with a plurality of longitudinally 15 extending ridges in order that the corners or ridges thereof might form the threads or twisted corners of the bar. When bars of this character have been so twisted, while hot, (but have not been rolled on their surfaces during the twisting operation) it has been found that strains are set up in the metal of the bar which frequently give way to breaks after the bar is cold and put to use. Furthermore, it has been found, by those skilled in the art, that when polygonal reinforcing-bars are molded in concrete mixtures, the concrete moves slightly away from the flat surfaces of the bar and is drawn in tightly against the corners thereof. This 20 lack of contact of the cement with the bar decreases the strength of the combination and it is often found that the cement at the corners of the bar is cracked, due to the excessive strain set up at the corners and the sharp edges thereof. Moreover, it has been 25 found that threads on a twisted bar which are more nearly at right angles with the axis of the bar give the best axial grip on the concrete. In order to produce this with a 30 twisted square or rectangular bar, it is necessary to greatly increase the number of twists, and thus increase the uncertainty of the physical properties of the finished twisted bar.

35 In producing my invention, the general object has been to overcome the objections above enumerated.

My apparatus produces bars from stock having a substantially round cross-section, and the threads thereon are formed by spiral rolling. This rolling greatly increases the

tensile strength of the finished product and also obviates any uncertainty as to the presence of strains in the finished product, which would be caused if the bar were produced by twisting the same. The bar which is produced by my apparatus has an oval cross-section which provides the best possible shaped surface for contact of the concrete, and also eliminates the danger of cracking the concrete at the corners. The rolling of my product is such as to bring the threads at a greater angle with the axis of the bar than is the case with the present twisted square bars, thus giving an increased axial grip on the concrete. The finished product is also straight throughout its length as it leaves the exit ends of the rolls.

Reference is to be had to the accompanying drawings, forming part of this specification, in which like characters of reference indicate like parts throughout the several views, of which:

Figure 1 is a plan view of the rolls of my apparatus, showing the upper roll in dotted lines and the lower roll in full lines and a bar passing therebetween in the process of being rolled. Fig. 2 is a sectional elevation of my apparatus, the section being taken of the lower roll, on line 2—2 of Fig. 1. Fig. 3 is a transverse section of the bar taken on line 3—3 of Fig. 1. Fig. 4 is a transverse section of the bar taken on line 4—4 of Fig. 1. Fig. 5 is a sectional elevation of the bar taken on the same line 3—3 of Fig. 1 as Fig. 3.

As shown in the drawings, the apparatus for forming my bar comprises an upper roll 5 and a lower roll 6. These rolls are superimposed, one above the other, and have their axes at preferably right angles to each other. Suitable means (not shown) are provided for rotatably mounting and driving these rolls in unison. The ends 7 and 8 of the rolls 5 and 6 respectively, are the entering ends of the rolls, and the ends 9 and 10 are the exit ends thereof. On each periphery of the rolls is provided a series of circumferential ridges. The ridges 11, 12, 13, 14, 15 and 16 start at the entrance ends 7 and 8 of the rolls, and, up to substantially the center, gradually increase in width from a very narrow ridge to substantially a width or size which is equal to the full width of the grooves on the bar as measured perpendicular to the helix. From substantially the center of the rolls to the

exit ends 9 and 10, the circumferential ridges 17 and 18 are of a width and a curvature substantially equal to the uniform width and curvature of the contacting 5 rolled surfaces of the bar as measured longitudinally. From the entrance and exit ends of the rolls the ridges decrease in diameter as they approach a plane midway between the ends so that the general contour 10 of the rolls is concave. The narrow ridges 11 and 12 at the entrance end of the rolls are preferably knurled so as to permit the rolls to grasp the bar as it is entering and feed it between and through the rolls 5 and 6.

In the drawings, 19 represents a bar passing through the rolls in the process of being rolled and having threads spirally formed thereon. This bar, as hereinbefore 20 stated, is of substantially round cross-section before being rolled. In this drawing, I show the end 20 of the bar as it is before being rolled, and the end 21 as it is after being rolled. It will be noticed that 25 from the entrance end of the rolls to substantially the center of the rolls, the bar has a groove gradually increasing in width. The bar is rolled with a double thread, each starting at substantially 180 degrees apart. 30 As the bar is passing through between the rolls, each successive ridge which acts upon it being wider than the preceding one, widens the grooves formed in the bar until the maximum is reached. Thus, it will be 35 seen that the groove 22 is started by the ridge 11 on the upper roll and the groove 23 is made by the ridge 11 on the lower roll. As the bar continues to travel, the groove 22 is engaged in succession by the ridge 12 40 of the lower roll, the ridge 13 of the upper roll, the ridge 14 of the lower roll, the ridge 15 of the upper roll, the ridge 16 of the lower roll, the ridge 17 of the upper roll, and then is engaged successively by the full 45 width ridges 18 of the upper and lower rolls. The groove 23 is started by the ridge 11 of the lower roll and is engaged in succession by the ridge 12 of the upper roll, the ridge 13 of the lower roll, the ridge 14 50 of the upper roll, the ridge 15 of the lower roll, the ridge 16 of the upper roll, the ridge 17 of the lower roll and then successively by the full width ridges 18 of the upper and lower rolls. The steps 24 in the 55 grooves 22 and 23 show the points of contact of the ridges of the upper roll with the bar as the same is traveling through between the rolls, thus clearly showing the successively increasing width of the grooves 60 formed in the product. As the product comes from the exit end of the rolls, it is provided with a double spirally disposed thread 25 extending around a bar having an oval or elliptical cross-section.

65 The pitch of the circumferential ridges

formed on the periphery of my rolls, as measured along the line of travel of the bar, is such as to correspond to the uniform pitch of the thread of the bar, and the gradually decreasing width of grooves 26 70 forms clearance spaces for the unrolled surface of the bar while it is passing through between substantially the first half of the rolls.

While I have shown and described my apparatus as applied to rolling of metal bars, 75 it is obvious that the same may be applied to the rolling of other products than those herein referred to, such other products having characteristics similar to those herein described. The angular relation of the axes of the rolls may be varied and made to suit any desired lead of the thread on the bar. These and other modifications of the details herein shown and described may be 80 made without departing from the spirit of my invention as set forth in the appended claims, and I do not wish to be limited to the exact embodiment herein shown and described. 85

Having thus described my invention, what I claim is:

1. An apparatus for making spiral-rolled bars, comprising two superimposed rolls having their axes at an angle to each other, 95 the periphery of each roll being provided with a series of circumferential ridges, said ridges decreasing in diameter as they approach a plane midway between the end of the rolls, whereby the general contour of the 100 rolls is concave.

2. An apparatus for making spiral-rolled bars, comprising two superimposed rolls having their axes at an angle to each other, the periphery of each roll being provided 105 with a series of circumferential ridges having a pitch, measured along the line of travel of the bar, which is substantially equal to the maximum pitch of the bar, said ridges decreasing in diameter as they approach a 110 plane midway between the end of the rolls, whereby the general contour of the rolls is concave.

3. An apparatus for making spiral-rolled bars, comprising two superimposed rolls 115 having their axes at an angle to each other, the periphery of each roll being provided with a series of circumferential ridges, said ridges gradually increasing in width from the entrance end of each roll to a width 120 near the center of each of said rolls, which, when measured along the axis of the bar is substantially equal to the full pitch of the bar, the first of the narrow ridges at the entrance end of the rolls being knurled, and said ridges decreasing in diameter as they approach a plane midway between the ends of the rolls, whereby the general contour of the 125 rolls is concave.

4. An apparatus for making spiral-rolled 130

bars, comprising two superimposed rolls having their axes at an angle to each other, the periphery of each roll being provided with a series of circumferential ridges, said 5 ridges gradually increasing in width from the entrance end of each roll to a maximum width near the center of each of said rolls, which, when measured along the axis of the 10 bar is substantially equal to the full pitch of the bar, said ridges decreasing in diameter as they approach a plane midway between the ends of the rolls, whereby the 15 general contour of the rolls is concave.

5. An apparatus for making spiral-rolled bars, comprising two superimposed rolls having their axes at an angle to each other, the periphery of each roll being provided with a series of circumferential ridges, said 20 ridges gradually increasing in width from the entrance end of each roll to a width near

the center of each of said rolls, which, when measured along the axis of the bar is substantially equal to the full pitch of the bar, the remaining ridges from substantially the center of the rolls to the exit end of each 25 being of a width corresponding to the width of the uniform, finished grooves in the bar, as measured along its line of contact with the rolls, and said ridges decreasing in diameter as they approach a plane midway between the end faces of the rolls, whereby the 30 general contour of the rolls is concave.

In testimony whereof, I have hereunto signed my name in the presence of two subscribing witnesses.

FRANK H. WILLIAMS.
